Patented Feb. 6, 1923.

1,444,341

UNITED STATES PATENT OFFICE.

LAWRENCE R. GARLOCK, OF LOCKPORT, NEW YORK.

FUEL.

No Drawing.

Application filed November 3, 1920. Serial No. 421,439.

To all whom it may concern:

Be it known that I, LAWRENCE R. GARLOCK, a citizen of the United States, residing at Lockport, in the county of Niagara and 5 State of New York, have invented certain new and useful Improvements in Fuel, of which the following is a specification, reference being had therein to the accompanying drawing.

10 This invention relates to an improved fuel, and particularly to one which may be used as a substitute for gasoline.

The objects of the invention are to provide an improved fuel, preferably a gasoline 15 substitute, which will include comparatively inexpensive ingredients capable of being easily and quickly mixed, and one which will lend itself readily to a great many uses and particularly as a fuel for internal combustion engines.

It has been found in actual practice that a mixture containing the following ingredients, in the proportions given, produces a very high grade fuel: benzine, 48%; kerosene, 47.9%; ether, 3.5%, nitre .6%.

The ingredients may be mixed in any particular order, and the proportions may be varied to suit climatic conditions. It is to be understood that, in specifying the 30 portions, I do not wish to be limited to the same except as set forth in the appended claims.

When used as a fuel for automobiles, I have found that I secure an increase of between 25 and 30% in mileage at a saving of 35 about 20% over the present cost of gasoline.

The petroleum derivatives form the major portion of the mixture and tend to give body to the same; and the action of the various other ingredients is such that the addition 40 of the ether tends to vary the flash point of the mixture, offsetting the flash point of the kerosene. The function of the nitre is to purify the mixture, and it has, in addition, the effect of preventing the formation of 45 carbon.

What I claim is:

1. A fuel comprising a mixture of benzine, kerosene, ether, and nitre; the benzine and kerosene being in approximately equal proportions, and the ether and nitre being in 50 relatively small proportions.

2. A fuel comprising a gasoline substitute including the following ingredients in approximately the following proportions: benzine, 48%; kerosene, 47.9%; ether, 3.5%; nitre, .6%.

In testimony whereof I affix my signature in presence of two witnesses.

LAWRENCE R. GARLOCK.
